UNITED STATES PATENT OFFICE.

ALEXANDER THOMSON AND VEERIN B. DANIELS, OF SOUR LAKE, TEXAS.

SEAL FOR WELL-SCREENS AND MEANS FOR SETTING SAME.

1,382,255.

Specification of Letters Patent. Patented June 21, 1921.

Application filed November 23, 1920. Serial No. 425,957.

To all whom it may concern:

Be it known that we, ALEXANDER THOMSON and VEERIN B. DANIELS, citizens of the United States, residing at Sour Lake, in the county of Hardin and State of Texas, have invented certain new and useful Improvements in Seals for Well-Screens and Means for Setting Same, of which the following is a specification.

10 This invention has reference to improvements in seals for well screens and means for setting the same, and is designed to provide a permanent joint or seal between the screen section and the casing, and at the same time to allow full opening through the screen for the passage of a bailer or for tubing.

In the preferred form a feature of the invention finds embodiment in a ring of soft 20 metal so mounted that when the tubing is lowered to the desired depth into the well, the soft metal may be expanded or distended against the inner wall of the casing, forming a permanent, effective and indestructible 25 seal.

The invention will be best understood from a consideration of the following detailed description, taken in connection with the accompanying drawings forming a part 30 of this specification, with the further understanding that while the drawings illustrate a practical form of the invention, the latter is susceptible of other practical embodiments, and, therefore is not confined to any 35 strict conformity with the showing of the drawings, but may be changed and modified so long as such changes and modifications mark no material departure from the salient features of the invention.

40 In the drawings:—Figure 1 is a vertical sectional view of our improvement assembled in a well and before seal is distended. Fig. 2 is a similar view with the seal distended. Fig. 3 is a view partly in elevation 45 and partly in section of the seal expanding pipe and the well tubing. Fig. 4 is an end view of the same.

Referring to the drawings, there is shown a well casing 1, which is assembled to be 50 sunk to the desired depth. In Fig. 1 the upper end of a sleeve 2 is shown internally threaded left handed at 3 and connected with a drill pipe 4, which is assumed to be of a length to extend to the surface, and may 55 be of an appropriate number of sections for the purpose. In threaded engagement with

the lower end of the sleeve 2 is a coupling 5, to which, when setting a screen is usually connected one or more lengths of pipe 6, and to that the top end of the screen is connected; said pipe should extend upward a sufficient distance inside of the well casing to form a protected opening from screen to the casing.

A slidable collar 7 has its lower end bored 65 to fit loosely over the sleeve 2 and is counter-bored at 8 to pass over an annular enlargement 9 on the upper end of the sleeve 2. When thus assembled a lead ring 10 (Fig. 1) is cast on the sleeve 2 and it extends from 70 the coupling 5 to the collar 7. A short distance above the lower end of the drill pipe 4, two holes are drilled at points diametrically opposite, and threaded to receive pins 11 which extend through spirally formed 75 slots 12 formed in a short section of pipe 13, that is vertically slidable on pipe 4. The lower ends of the slots 12 start at opposite points on the pipe 13 and extend upward spirally one fourth of the distance around 80 said pipe in opposite directions as shown in Fig. 3, hence when pipe 4 is disengaged from the sleeve 2 and lifted, the pins will pass to the upper ends of the slots, and said ends being elongated vertically as shown at 14, 85 retain the pins in said ends and permit of pipe 13 being raised by pipe 4 and dropped upon the collar 7, which expands the lead ring as shown by 10' (Fig. 2) effectually closing the passage between the casing and 90 the parts left connected with the screen.

In the operation of the device, the parts as assembled for placing in a well are shown in Fig. 1, coupling 5 being connected with one or more joints of pipe 6, to which a suitable screen or strainer is attached, and sufficient pipe coupled to pipe 4 to reach the surface. When the screen is set at bottom of well and the well has been bailed, the pipe at surface is turned right hand, and as their 100 is sufficient friction on screen and joint or more of pipe to which it is connected to prevent same from turning, it will release left hand thread 3, allowing the pipe 4 to rise, and pipe 13 to assume and be locked in the 105 relative position shown in Figs. 2 and 3, with the threaded end of pipe 4 receded above the end of 13. Then pipe 4, carrying the section 13, is lifted a few inches and 13 dropped on top end of collar 7 which forces 110 it downward, causing expansion of the lead and effecting a permanent seal between the

sleeve 2 and the casing; when the pipe 4 with section 13 may be drawn from the well.

The present method of sealing between a screen and the casing is to use a right and left hand threaded coupling, with left hand thread at top, and casting a lead collar on top half, with lead projecting above the coupling. When the left hand thread is released from the set pipe and the pipe withdrawn, a cone-shaped tool is attached and let into the well and dropped on the lead, flaring it funnel shaped, which makes an uncertain joint as it permits a very light pressure from below to pass it, with probable loss of the well.

With our invention the lead is set out or sealed before set pipe is withdrawn from the well, and when withdrawn it is not necessary to put it back again and therefore saves much time and expense.

When necessary or desired to remove the screen from a well, a hollow tapered tap is used to screw in the top of sleeve 2, when all the attached parts may be withdrawn. It is also noted that the top end of collar 7, also of sleeve 2 are chamfered inside, making a fair approach for bailer or tubing when entering the screen.

While we prefer lead as a sealing material, as it flows readily under pressure or impact, and is unaffected by acids, being practically indestructible, it will be understood that the invention embraces any and all other well known materials capable of substitution therefor.

Having thus described our invention, we claim as new and desire to secure by Letters Patent:

1. A seal for well screens and means for setting same comprising a carrying means for the screen having a coupling at its upper end, and a sleeve member connected with the coupling, a collar slidable on said sleeve, an expandible ring between the coupling and sleeve, said slidale collar being arranged to expand the expandible ring when in place into engagement with the interior of the well casing.

2. A seal for well screens and means for setting same in well casings with the screen section provided with a coupling at its upper end, a sleeve member connected with said coupling, a collar slidale on said sleeve, an expandible ring between the coupling and sleeve, and a pipe section having left hand threads at its lower end adapted to screw into the sleeve structure, a short pipe section receiving the first named pipe in telescoping relation thereto, the first named pipe having two threaded pins diametrically opposite which extend through spirally formed slots formed in the second named pipe for constraining the two pipes to travel vertically in unison, and when raised and dropped, cause the last named pipe to contact the collar and expand the expandible ring into engagement with the interior of the well casing.

3. A seal for well screens and means for setting same in well casings comprising one or more joints of pipe connected with the top end of a well screen and extending in the casing, a coupling attached to the upper end of said pipe, a sleeve in threaded engagement with the other end of said coupling, a slidale collar on the sleeve, a lead ring cast about the sleeve filling the space between its lower end and the upper end of said coupling and exteriorly flush with both, a left hand thread in the upper end of the sleeve adapted to receive the lower end of a drill pipe, a short section of pipe receiving the said pipe in telescoping relation thereto, the first named pipe having two threaded pins oppositely disposed and extending through spirally formed slots in the second named pipe and adapting them, when released from the sleeve to move in unison, and when raised and dropped cause the last named pipe to contact the collar and expand the lead ring, for the purpose set forth.

In testimony whereof we affix our signatures.

ALEXANDER THOMSON.
VEERIN B. DANIELS.
